ADJUSTABLE TRIM TAB FOR LEVELING A BOAT

Gerald J. Curtis, 8806 Glen Loch, Houston, Tex. 77017

Filed Feb. 4, 1974, Ser. No. 439,131

Term of patent 14 years

Int. Cl. D12—99

U.S. CL. D12—70

FIG. 1

FIG. 2

FIG. 3

FIG. 4

FIG. 5

FIG. 1 is a perspective view of the adjustable trim tab for leveling a boat of the present invention;

FIG. 2 is a top view;

FIG. 3 is a front view;

FIG. 4 is a bottom view;

FIG. 5 is an end view; and,

FIG. 6 is a back view of the adjustable trim tab design of the present invention.

I claim:

The ornamental design for an adjustable trim tab for leveling a boat, as shown.
